GUSTAV B. PETSCHÉ, OF YONKERS, NEW YORK.

ROTARY PUMP.

1,380,015.

Specification of Letters Patent. Patented May 31, 1921.

Application filed October 6, 1920. Serial No. 415,141.

To all whom it may concern:

Be it known that I, GUSTAV B. PETSCHÉ, a citizen of the United States of America, and a resident of Yonkers, in the county of 5 Westchester and State of New York, have invented a certain new and useful Improvement in Rotary Pumps, of which the following is a true and exact description, reference being had to the accompanying drawings, 10 which form a part thereof.

My invention relates to rotary pumps or compressors of the type in which the rotating piston consists of an eccentric ring contacting with the walls of the pump cylinder 15 and provided with an extension forming a partition between the admission and delivery ports of the pump. The object of my invention is partly to provide such a pump with a sliding grid iron delivery valve having means by which it is opened when the pressure on the delivery side of the pump equals the pressure in the receiver and means for closing the valve actuated by the 20 rotating eccentric ring piston and acting to close the valve at the time that the pump piston completes a compression cycle. In its broader side my invention relates to the means used to close the delivery valve irrespective of the special construction of such a 25 compressor but it also relates to that special form of such compressors where the piston extension forms a slide working in a swivel block.

The nature of my improvements will be 30 best understood as described in connection with the drawings in which they are illustrated and in which—

Figure 1 is a side elevation of my improved pump taken as on the section line 40 1—1 of Fig. 2.

Fig. 2 is a front elevation of the pump partly in section on the line 2—2 of Fig. 1, and

Fig. 3 is a face view of the grid iron valve 45 and its attachments.

A and A' indicate two pump cylinders formed in a single casting and provided with face plates A² and A³. A⁴ indicates the cylindrical surface of the cylinders. B 50 is a bearing in the casing for the swivel block; B' is the admission chamber and B² the delivery chamber which chambers can be common to both of the pair of pumps. C is a passage or chamber formed in the casing having a port C' leading into it from

the delivery side of the pump and a port C² leading from it into the delivery chamber. D is the driving shaft to which are secured eccentrics D' which are surrounded by eccentric ring pistons E provided at their upper ends with slides F which, as shown, have openings F' formed in them leading from the admission chamber B' and communicating through a port F² with the admission side of the cylinder. This construction is preferred by me though, broadly speaking, my invention can be utilized with pumps having admission ports formed through the walls of the cylinder. N indicates the swivel block through which the 60 slide F works and which has its bearing in the cylindrical bearings indicated at B. G is a valve casing or bushing fitting in the chamber C and having extending across said chamber a grid iron valve seat G'. H 65 is a grid valve seated on the seat G' and having, as shown, a valve stem H' to which are secured a piston I and a plunger I'. J is a dash pot cylinder in which the piston I works, this cylinder having restricted ports 70 J' and J² leading from its opposite ends and communicating with each other through an adjusting block J³. K is a cylinder in which works the plunger I', the end of this cylinder connecting through a pipe L with 75 the delivery side of the cylinder. By preference, I connect this pipe with the port L' located at a point in the surface A⁴ of the cylinder which is crossed by the contacting line with the piston at the same time that 80 the piston comes in contact with the means to be described for closing the valve. The cylinder K, however, can connect with the pump cylinders at other points, for instance, as shown in dotted lines, with the port C'. 95 M is the pivot of the lever M' and M², M' of which engages the grid valve, as shown, while the arm M² of the lever extends through the port C' and lies in the path of the rotating piston so as to contact with it 100 and close the valve. At the end of the compression cycle of the pump I have indicated in dotted lines the position to which this arm of the lever is moved by the piston.

In operation air is admitted to the receiving side of the pump cylinder and preferably I admit the air, as shown, through the slide F for the reason that in this way the pressure which is incident to a slide leading into a receiving chamber is avoided. 110

This feature of the construction illustrated is not specifically claimed in this case but is claimed in my co-pending application for Letters Patent filed October 6, 1920, Serial No. 415,145. It will be observed that the location of the port F^2 in slide F is such that it is closed during the period when the rotating piston is passing from the completion of one cycle to the beginning of another and 10 when some compressed air which has not passed the delivery valve would be free to mix with the air drawn in preparatory to the second cycle. This feature, also, I believe to be new with me and it is claimed in 15 my before mentioned co-pending application.

It will be obvious that the valve H is held on its seat in closed position by the pressure of the fluid in the receiver and that as the piston E proceeds with its compressing 20 cycle the pressure will build up on the under side of the valve and also, passing through the pipe L build up in the cylinder K which is so proportioned that when the pressures on both sides of the valve are substantially 25 equal the pressure exerted on the plunger I' will be sufficient to shift the valve to open position. After the pump piston has substantially completed its work it is desirable that the pressure should be cut off from the 30 cylinder K and therefore I preferably locate the port L' communicating with the pipe L at a point which is crossed by the piston at the same time that the piston comes in contact with the lever for closing the valve. 35 At this point the piston contacts with the arm M^2 of the lever M' , M^2 , and this further movement shifting this lever to the position shown in dotted lines and through the lever arm M' shifts the grid valve to a 40 closed position. The dash pot cylinder J and the piston I attached to the valve rod serve to cushion the movements of the valve by oil in the cylinder flowing through the 45 passages J' and J^2 and a plug J^3 from one side to the other of the cylinder.

Having now described my invention, what I claim as new and desire to secure by Letters Patent, is:

1. In a rotary pump having a cylinder a 50 rotating eccentric ring piston and a slide extending from said piston through a swivel block and an admission port, a delivery passage in the cylinder casing having a grid valve seat, a grid valve working on said seat to open and close the delivery passage, a 55 plunger secured to the valve stem, a cylinder for said plunger connected to the pump cylinder at or near the delivery port and means for closing the valve lying in the path of the pump piston and contacting with it at 60 the end of its delivery cycle.

2. In a rotary pump having a cylinder a 65 rotating eccentric ring piston and a slide extending from said piston through a swivel block and an admission port, a delivery passage in the cylinder casing having a grid valve seat, a grid valve working on said seat to open and close the delivery passage, a 70 plunger secured to the valve stem, a cylinder for said plunger connected to the pump cylinder at or near the delivery port, a dash pot cylinder and piston working in connection with the valve to cushion its movements and means for closing the valve lying in the 75 path of the pump piston and contacting with it at the end of its delivery cycle.

3. In a rotary pump having a cylinder a 80 rotating eccentric ring piston and a slide extending from said piston through a swivel block and an admission port, formed through the slide, a delivery passage in the cylinder casing having a grid valve seat, a grid valve working on said seat to open and close the delivery passage, a 85 plunger secured to the valve stem, a cylinder for said plunger connected to the pump cylinder at or near the delivery port and means for closing the valve lying in the path of the pump piston and contacting with it at the end of its 90 delivery cycle.

4. In a rotary pump having a cylinder a 95 rotating eccentric ring piston and a slide extending from said piston through a swivel block and an admission port, a delivery passage in the cylinder casing having a grid valve seat, a grid valve working on said seat to open and close the delivery passage, a 100 plunger secured to the valve stem, a cylinder for said plunger connected to the pump cylinder at a point in the pump cylinder 105 crossed by the rotating piston at or about the time that the piston contacts with the valve closing means and means for closing the valve lying in the path of the pump piston and contacting with it at the end of its 110 delivery cycle.

5. In a rotary compressor having a rotating eccentric ring piston and an extension of said piston forming a partition between the admission and delivery ports of the compressor, a delivery passage in the cylinder casing having a grid valve seat, a grid slide valve working on said seat, means for moving the valve to open it operating at the 115 end of the compression cycle of the piston and means for closing the valve lying in the path of the eccentric ring piston and contacting with it at the end of its delivery cycle.

GUSTAV B. PETSCHE.
